Primary Examiner — Deanna L Pratt*Assistant Examiner* — Natasha Vujcic(74) *Attorney, Agent, or Firm* — Oliff PLC(57) **CLAIM**

The ornamental design for a vehicle step, as shown and described.

DESCRIPTION

FIG. 1 is a perspective view of a vehicle step;

FIG. 2 is a front view thereof;

FIG. 3 is a top view thereof;

FIG. 4 is a right-side view thereof;

FIG. 5 is a left-side view thereof;

FIG. 6 is a rear view thereof; and,

FIG. 7 is a bottom view thereof.

The broken lines in the drawings illustrate the environment of the vehicle step and form no part of the claimed design.
